UNITED STATES PATENT OFFICE.

JOSEPH DYKMAN, OF BRUSSELS, BELGIUM, ASSIGNOR TO SOCIÉTÉ ANONYME
IMEXINEL, OF BRUSSELS, BELGIUM.

ELECTRIC LIQUID HEATER.

Application filed January 16, 1924. Serial No. 686,549.

To all whom it may concern:

Be it known that I, JOSEPH DYKMAN, subject of the King of the Belgians, residing at 320 Avenue de Tervueren, Brussels, Belgium, have invented certain new and useful Improvements in Electric Liquid Heaters, of which the following is a specification.

The present invention has reference to an apparatus in which the flow of an electric current through a resistance is used for heating liquids and more particularly running water. It has for its chief object to heat the liquid by direct contact with the resistance, while avoiding the objectionable effects of electrolysis and polarization. Moreover, suitable provisions are made to prevent deterioration of the resistance and contacts and to obtain an efficient insulation between parts at different potentials.

To this end the apparatus according to this invention comprises an insulating body of cylindrical or other suitable shape having a helical groove which is used both for conveying the liquid and for accommodating the resistance. The ends of the resistance are respectively connected to two terminals, one directly and the other through the intermediary of a rod extending through the insulating body. An insulating sleeve of flexible or rigid material closely surrounds the insulating body and forms a watertight joint with the edges of the groove.

The two terminals are respectively connected to conductors supplying the electric current and a switch is inserted in one of said conductors. The operating member for said switch also controls the operation of a valve inserted in the conduit supplying the liquid, for example water, to the insulating body so as to simultaneously cut off the flow of water and the flow of electric current, while permitting of regulating the supply of water without breaking the electric circuit.

The terminals, the switch and the valve are mounted on an insulating supporting block and protected by a cap or cover secured to said block. On the other hand the rod which extends through the insulating body is also secured at one end to the supporting block and at its other end it carries nuts for securing in position a collecting receptacle for the heated liquid and protecting casings.

With the above arrangement the liquid travels for a long distance in direct con-

tact with the resistance, the two poles of which are located at the ends of this distance so that they are sufficiently insulated to practically annul the effects of electrolysis. The connection between the regulating valve and the switch permits of varying at will the temperature of the liquid and the simultaneous cutting of the liquid and electric currents precludes the burning of the resistances. Further the mounting of the apparatus is simple, the insulation is efficient and the thermic efficiency extremely high.

In the accompanying drawing which illustrates by way of example an apparatus constructed according to the invention:

Fig. 1 is a vertical section of the apparatus on line A—B of Fig. 3.

Fig. 2 is a partial vertical section on the broken line C—D of Fig. 3.

Fig. 3 is a horizontal section on line E—F, Fig. 1.

The apparatus illustrated essentially comprises a supporting block 1 of insulating material on which are secured the valve 2, the terminals 21, 22 and the fixed contacts 3 of the switch. In the base of block 1 is screwed a metal rod 4 extending through the insulating body 5 which is pressed against the block 1 by a nut 46 screwed on the threaded lower end of the rod 4.

The insulating body 5 consists preferably of a cylindrical mass of porcelain provided with a helical groove 6 on its outer surface. It is closely surrounded by an insulating sleeve 7, of flexible or stiff rubber for example, forming with the edges of groove 6 watertight joints which may be cemented if necessary. At its lower end the sleeve 7 has a small flange which fits into a circular groove 8 in the body 5, while the upper end of the sleeve closely fits around the base of block 1 and against a packing gasket 10.

On the lower end of rod 4 is screwed an internally threaded cap 9 which holds a protecting casing 11 surrounding the sleeve 7, the lower end of said casing forming a cup-shaped receptacle 12 for collecting the hot water. The cap 9 ends in a threaded sleeve 13 on which is screwed the discharge nozzle 14 which is also used to press against the base of block 1 an outer casing 15 enclosing all the parts located below the said block.

At the top of the groove 6 opens a duct 16 bored through the block 1 and connected

to a lateral nozzle 48 of the valve casing 2. A conical plug 17 with axial inlet and lateral outlet controls the delivery of the water fed through a nozzle 18 integral with the casing 2 and adapted to be connected to a suitable source of supply. Water tightness is efficiently secured on the one hand by a packing ring 49 pressed against the plug 17 by a bushing 50 screwed into the nozzle 48 and 10 on the other hand by a packing ring 51 surrounding the valve spindle 32 and pressed by a threaded cap 19.

In the groove 6 is located the resistance 20 consisting of a thin coiled wire of great 15 length. One end of the wire 20 is directly connected to the terminal 21 (Fig. 2) while the other end is connected to the rod 4 which is connected at the top with the terminal 22 by means of the screw 23 and contact 20 piece 24. To the terminal 21 is connected one of the current supply wire 25, while the other wire 26 divides into two wires connected each to one of the fixed contacts 3 of the switch. The movable contact 27 of 25 the switch is connected to the terminal 22 and it is shaped as a blade pivoted at 28 to an insulating contact carrier 29 and connected by a spring 30 to an arm of said contact carrier. When the switch is opened the 30 sudden operation of the blade 27 by the spring 30 instantaneously breaks the circuit.

The contact carrier 29 is secured to two shafts in alignment with and insulated from each other, one of said shafts consisting of 35 the valve spindle 32, and the other shaft 33 being provided with an operating handle 34. This handle thus permits of simultaneously controlling the circulation of water and the flow of electric current. The 40 spring 30 is so proportioned that when the switch is closed a slight rotation of the shaft 33 will cause the delivery through the valve 2 to vary without interrupting the electric current, the contact 27 being 45 operated by the spring 30 only when the flow of water is stopped. The handle 34 is secured to the shaft 33 by a collar 35 pressed by a spring 36 against a graduated plate 37, said collar carrying a finger or spring 38 50 adapted to move opposite the graduations on plate 37 and to indicate the position of the valve plug.

The parts mounted on the block 1 are 55 protected by a cap 39 bearing on an upstanding flange 41 of said block in which are mounted the shaft 33 and the nozzle 18. The cap 39 is secured in position by a knob 40 screwed on a threaded pin 42 on a yoke 43 secured to the block 1 by screws 44 (Fig. 3).

60 The operation of the apparatus is as follows:

When the handle 34 is operated to close the switch and open the valve, water under pressure admitted axially of the plug 17 65 issues laterally therefrom, passes through

the duct 16 into the groove 6 and follows the said groove around the insulating body 5 until it reaches the lower end thereof. It then passes through the bore 45, the cup 12, opening 47, cap 9, sleeve 13 and escapes 70 through the nozzle 14. On the other hand an electric circuit is closed between the wires 25 and 26 through terminal 21, resistance 20, rod 4, screw 23, contact member 24, terminal 22 and the contacts 21 and 3 of the 75 switch. The water in groove 6 is in contact with the resistance 20 over a long distance and it becomes heated as it absorbs the calories given off by the resistance. The temperature of the water delivered through 80 the nozzle 14 can be regulated by varying the flow of water by means of handle 34. When such flow is stopped the electric current is also cut off by the action of spring 30 as explained above. 85

It is of course understood that various modifications may be made in the apparatus described without departing from the spirit of the invention.

I claim:

1. In an electric liquid heater, the combination of a cylindrical insulating body having a helical groove along its lateral surface, an insulating block on the top of said body, a pair of terminals on said block, a resistance in said groove extending along the whole length thereof, a threaded metal rod extending through said body and screwed into said block, one of said terminals being directly connected to the upper end of said resistance, the other terminal being connected to the lower end of said resistance through the intermediary of said rod, a sleeve closely surrounding the edges of said groove, an inner casing surrounding said sleeve, the lower end of said casing forming a cup-shaped receptacle connected to the lower end of said groove, a cap screwed on the free end of said rod for securing said casing in position, a threaded sleeve integral with said cap, an outer casing bearing on said block, said outer casing forming a heat-insulating air chamber around said inner casing, a discharge nozzle screwed on said sleeve and adapted to secure said outer casing in position, and a connection between said receptacle and nozzle through said cap and sleeve. 105

2. In an electric liquid heater, the combination of an insulating body having a helical groove along its lateral surface, an insulating block on one end of said body, a resistance in said groove extending along the whole length thereof, a valve on said block for admitting a flow of liquid to said groove, a switch on said block for sending electric current through said resistance, a pair of terminals on said block, one of said terminals being directly connected to one end of said resistance, a metal rod extending 110 115 120 125 130

through said body and into said block, said rod forming both an electrical connection between the other end of said resistance and the other of said terminals and a mechanical connection between said body and said block, means for simultaneously operating said valve and switch, and a spring inter-

posed between said operating means and switch for permitting limited movement of said valve independently of said switch and producing a sudden operation of said switch. 10

JOSEPH DYKMANS.
